FIG. 3.

INVENTOR

William J. Mecke
by Francis D. Pastries
Solicitor

UNITED STATES PATENT OFFICE.

WILLIAM J. MECKE, OF CAMDEN, NEW JERSEY.

WALKING-STILT.

SPECIFICATION forming part of Letters Patent No. 469,641, dated February 23, 1892.

Application filed October 5, 1891. Serial No. 407,707. (No model.)

To all whom it may concern:

Be it known that I, WILLIAM J. MECKE, a citizen of the United States, residing at Camden, in the county of Camden and State of New Jersey, have invented a new and useful Improvement in Walking-Stilts, of which the following is a specification.

The object of my invention is a walking-stilt the step of which can be readily adjusted on the pole for persons of varying heights.

The invention consists in the combination, with a notched pole, of a step recessed to fit over the inner side of the pole, and is composed of a back to which is fitted a tread supported by a bracket between it and the back and fillets in the intersection of said back and tread on both sides of the bracket. A suspender carries and holds the step in intimate contact with the pole by dropping into the notches and springing its loose ends into openings formed in the fillets.

On reference to the accompanying sheet of drawings, forming part of this specification, Figure 1 is a side view of a stilt embodying my invention. Fig. 2 is an outside view of the pole, showing its notches. Fig. 3 is a perspective view of the step, and Fig. 4 is a plan view of the suspender.

Similar letters refer to similar parts in the several views.

A is the pole of the stilt, which is notched in its outer side, as shown at a b.

B is the step, recessed at c to fit over the pole, by which an intimate contact is ob-

tained and the step braced against turning. Said step is composed of the back d, tread e, supporting-bracket f between the back and tread, and fillets g, fitted in the intersection of the back and tread on opposite sides of the bracket.

C is a rectangular suspender, preferably of metal, which is open at one of its sides for forming the opposing ends h. When the step B is suitably adjusted on the pole A, the suspender C is passed over said pole, so as to embrace it and the step by dropping its closed side into either of the notches a b and springing its loose ends h into the openings i of the step-fillets g, by which the pole and step are held in contact.

I claim—

In a walking-stilt, the combination of a pole A, which is notched in its outer side at a b, an adjustable step B, composed of the recessed back d, tread e, supporting-bracket f, 55 fillets g, and an open suspender C, which embraces the pole and step and binds them in intimate contact by dropping its closed side into the notches of the pole and springing its loose ends h into the openings i of the fillets, 60 substantially as shown and described.

In testimony whereof I affix my signature in presence of two witnesses.

WILLIAM J. MECKE.
